UNITED STATES PATENT OFFICE.

LOUIS B. PRAHAR, OF MASSAPEQUA, NEW YORK.

SPRING-FASTENER FOR BOXES, &c.

1,177,269.

Specification of Letters Patent. Patented Mar. 28, 1916.

Application filed October 27, 1915. Serial No. 58,130.

To all whom it may concern:

Be it known that I, LOUIS B. PRAHAR, a citizen of the United States, and a resident of Massapequa, in the county of Nassau and State of New York, have invented certain new and useful Improvements in Spring-Fasteners for Boxes, &c., of which the following is a specification.

This invention relates to certain improvements in spring fasteners for boxes, cigarette cases, pocket-books, or the like, and the object of the invention is to simplify the construction, reduce the number of parts, steps in operation and the cost of manufacture and assembly.

My invention is particularly applicable to metal cigarette cases although it is of course evident that it might be employed for holding together any two sections or hinged parts.

My invention involves certain details of construction, certain forms of which are shown in the accompanying drawings to which reference is to be had and in which similar reference characters indicate corresponding parts in the several views.

In these drawings, Figure 1 is an edge view of a cigarette case having a fastener constructed in accordance with my invention; Fig. 2 is a transverse section on the line 2—2 of Fig. 1; Fig. 3 is a transverse section on the line 3—3 of Fig. 1; Fig. 4 is a perspective view of the catch member separate from the case; Fig. 5 is a perspective view of a modified form of catch member; and Fig. 6 is a section similar to Fig. 2, but embodying the form of catch shown in Fig. 5.

In the accompanying drawings, I have shown my invention as applied to a sheet metal cigarette case including two sections 10 and 11 connected by a spring hinge 12. Each section is stamped from a single piece of sheet metal so as to provide a flat body portion and a peripheral flange portion, the flange portions of the two sections meeting to form the peripheral wall of the box.

I do not claim any novelty in the box itself and I wish it understood that my invention may be applied to boxes of other form, shape and construction.

My improved spring fastener, in the form shown in Figs. 1 to 4 inclusive, includes a single piece of sheet metal having the necessary thickness to give the required strength and having the necessary resiliency to in-

sure ease and certainty of operation. The fastener member includes an elongated body portion 13 adapted to lie along the inner surface of the wall of one section, for instance the section 10, adjacent to the free edge thereof. At one end, the body portion has two flanges 14 and 15 integral therewith and preferably extending from opposite edges. The flange 14 is bent to lie in a plane substantially at right angles to the plane of the body portion and extends outwardly through a slot in the wall of the case section 10. The other flange 15 is bent to lie approximately parallel to and just inside of the wall of the opposite section 11 of the case. The flange 15 is so constructed as to interlock with the section 11 and, when in normal position, hold the two sections together. In the specific form illustrated, the flange 15 is provided with an aperture 16 adapted to snap or spring over a projection 17 extending inwardly from the case section 11. Although the projection 17 may be formed integral with the case section 11, I have shown it as a stud extending through the wall and riveted thereto. I have shown the flange 15 as having an aperture to slip over this stud and receive it, but it is of course evident that the flange 15 might be in the form of a stud which would snap over the edge of an aperture or behind a shoulder on the section 11. As the flange 14 is at right angles to the plane of the body portion, pressure applied to the outer end of the flange will force the body portion inwardly from the wall of the section 10 and will disengage the flange 15 from the projection 17. At the same time any tendency of the case to open when the fastener is in position, will tend to pull the body portion 13 of the fastener laterally substantially in its own plane, but such pulling strain is resisted by the engagement of the flange 14 within the aperture in the wall. For attaching the fastener member to the wall of the casing, the body portion 13 is provided with a flange 18 adjacent to the opposite end from that bearing the flanges 14 and 15. The flange 18 is struck up from the center of a recess so as to lie in substantially the same plane as the flange 14. The flange 18 is very much smaller and shorter than the flange 14 and is designed to project through an aperture in the wall and to have its extremity then riveted over so as to hold the fastener member in position in the case. It

will be noted that the flange 18 lies in a plane substantially midway between the side edges of the body portion so that said body portion cannot be loosened or displaced by 5 a return bending of the flange 18 to the plane of said body portion.

It will be noted that all three of the flanges are bent along lines extending in the general direction of the length of the member. This is important as the metal is thin 10 and resilient and the angles through which the metal is bent approach or equal 90°. The member is cut from the stock so that the grain of the metal is lengthwise of the body portion. All of the bending thus comes 15 along the grain rather than transversely thereof and I thus materially reduce the liability to breaking of the parts during bending or while in use.

In the form shown in Figs. 1 to 4 inclusive, the body portion 13 lies substantially flat against the surface of the wall of the case. This is not essential as the body portion may be set edgewise. Thus, less 20 metal may be employed in its manufacture.

In the specific form shown in Figs. 5 and 6, I have shown a fastener member in which the body portion 13a lies in a plane at right angles to the plane of the adjacent wall to 25 which it is attached. This permits the flange 18a to lie in the same plane with the body portion and necessitates a slightly different bending of the flanges 14a and 15a.

Having thus described my invention, what 30 I claim as new and desire to secure by Letters Patent is:

1. The combination with two hinged members, of a fastener formed of a single piece

of sheet metal including a spring body portion, a lug at one edge thereof, spaced from 40 one end and projecting through one of said members and riveted to retain said fastener in position, a lug at the opposite end of said body portion and adapted to coöperate with the other member, and a third lug adjacent 45 to the last mentioned lug and projecting through the wall of the member to which said fastener is secured and serving as means for disengaging the second mentioned lug, each of said lugs being bent to lie at an 50 angle to the plane of said body portion.

2. The combination with two hinged members, of a fastener formed of a single piece of sheet metal including a spring body portion, a lug projecting through one of said 55 members and riveted to retain said fastener in position, a lug at the opposite end of said body portion and adapted to coöperate with the other member, and a third lug adjacent to the last mentioned lug and projecting 60 through the wall of the member to which said fastener is secured and serving as means for disengaging the second mentioned lug, said second mentioned lug and said third 65 mentioned lug being formed at opposite edges of said body portion and bent to project in opposite directions from the plane thereof.

Signed at New York in the county of New York, and State of New York this 70 26th day of October, A. D. 1915.

LOUIS B. PRAHAR.
